UNITED STATES PATENT OFFICE.

LEE GARDNER, OF CONCORD, NORTH CAROLINA, ASSIGNOR OF FORTY-FIVE ONE-HUNDREDTHS TO JOSEPH F. CANNON, GOWAN DUSENBERY, AND MORRISON H. CALDWELL, ALL OF CONCORD, NORTH CAROLINA.

HYDROCARBON-BURNER.

1,240,333.

Specification of Letters Patent. Patented Sept. 18, 1917.

Application filed December 24, 1915. Serial No. 68,558.

To all whom it may concern:

Be it known that I, LEE GARDNER, a citizen of the United States, residing at Concord, in the county of Cabarrus and State of North Carolina, have invented certain new and useful Improvements in Hydrocarbon-Burners, of which the following is a specification.

This invention relates to hydrocarbon burners, and more particularly to liquid fuel burners of that type in which a water reservoir is associated with the burner.

The primary object is to provide an improved construction of burner in which the flame from the burning fuel is caused to impinge upon the surface of the water in such reservoir, enter into the water, and convert the same into vapor, the latter uniting with the burning fuel and producing an intensely hot flame.

Other objects of the invention are to provide improved devices for governing and controlling the character of the flame produced by the burner, and for adapting it to various uses.

In order that the invention may be clearly understood, reference is had to the accompanying drawings, in which,

Figure 1 is a vertical section through my improved burner, showing one form of flame modifying device used in connection therewith;

Fig. 2 is a plan view of such flame modifying device;

Fig. 3 is a vertical section through the burner itself, showing a different arrangement of flame controlling device;

Fig. 4 is a vertical section through a modified form of chimney, and illustrates improved means for controlling the supply of air to the flame inside of such chimney;

Fig. 5 is a fragmentary plan view of one of the flame controlling devices shown in Fig. 4;

Fig. 6 is a fragmentary elevation of another one of said devices; and,

Figs. 7, 8, and 9 are fragmentary details showing my improved draft controlling device;

Fig. 10 is a fragmentary view similar to Fig. 1, showing my preferred construction.

Referring to the drawings in detail, and more particularly to Figs. 1, 2, and 3, my

improved burner comprises an outer water reservoir or pan 1, in which the water level is maintained substantially constant, as indicated at *w*, preferably by means of a float valve 2, controlling the supply of water from a pipe 3.

Seated in the pan 1 and slightly spaced from the bottom thereof is the burner proper. This consists of a drum 4, having an opening 5 in its bottom through which water may enter the interior of the drum. The upper part of the drum, above the water level, is provided with a large number of relatively small perforations 6, for the admission of air.

Inside of the drum 4 is secured an annular wall 7 of slightly smaller diameter than the drum, whereby an annular space or trough 8 is formed between such wall and the outer wall of the drum. It will be noted that the wall 7 extends to a point slightly above the lowermost of the perforations 6, and that it forms a chamber or basin in which the water stands at the same level as in the outer pan 1. Liquid fuel is fed into the annular space 8 through a pipe 9, in which is interposed any suitable form of regulating valve 10.

A second drum 11, preferably somewhat tapering in form, is disposed inside of the drum 4 and extends slightly above the same. This drum 11 is supported, as by means of clips 11^a, at a distance above the annular wall 7 so that a space 14 is provided between the upper edge of the wall 7 and the lower edge of the drum 11. This drum 11 is provided near its bottom with a series of relatively large perforations or openings 12.

Instead of making the drums 7 and 11 of equal size, as shown in Fig. 1, I may and preferably do make these drums as shown in Fig. 10. By reference to this figure, it will be seen that the lower edge of drum 11' is considerably smaller than the upper edge of drum 7, thus forming a horizontal space 14' through which the flame passes, as hereinafter described.

In order to get the proper draft, with the arrangement of parts shown, a chimney 20 of suitable height is provided and is supported upon an annular ring 19, which snugly surrounds the upper end of the drum 11 and fits over the upper edge of the drum

4. Thus, the only means by which air can enter the combustion chamber inside of the drums is through the perforations 6.

In Fig. 1 I have shown means for thoroughly mixing the gas and air, and for imparting a rotary motion to the column of combustible mixture and flame. This means consists of a pair of baffle plates 15 and 17, separated by a spacer 16, and supported in the upper part of the drum 11 by means of a suitable bracket 16^a, resting upon the bottom of the drum 4. The upper baffle plate 17 is preferably the larger, as shown, and substantially fills the upper end of the drum 11. The baffle plates 15 and 17 are similar in construction and, as will be seen by reference to Fig. 2, each comprises a central portion surrounded by a series of blades or fins. These blades are set at an angle after the manner of a windmill, with the result that a column of gas passing upwardly therewith is given a whirling or rotary motion.

The liquid fuel in the trough 8, having been ignited through a suitable lighting opening (not shown), the drums become filled with flame. Owing to the draft of the chimney, converging jets or currents of air are drawn in through the openings 12, and there is also a tendency for air to flow inwardly through the space 14 in Fig. 1, or the space 14' in Fig. 10. As a result of these air currents, the flame is caused to curl downwardly over the edge of the wall 7 of the water basin, and to impinge upon the surface of the water contained in such basin. This is particularly true in the arrangement shown in Fig. 10, in which the flame is directed downwardly through the horizontal opening 14'. The water is thus soon heated to the boiling point and the vapors, mixing with the oil gas, pass upwardly with the flame through the baffle plates and chimney, uniting with the burning fuel and producing an intensely hot flame. Considerable water is consumed from the inner basin, but the level is maintained on account of the opening 5 in the bottom. I have found that with some arrangements of flame controlling devices, and under certain conditions, equal quantities of water and oil are used.

In Fig. 3, I have shown my improved burner without a chimney, and I have found that it can be successfully operated in this condition. Here, however, I employ a flame condenser 21, which is in the nature of a plate resting upon the top of the drum 11, and provided with a relatively small central opening 22, through which the flame is forced to pass. A small drum 23, with a closed top, fits over the opening 22 and is provided with perforations 24 in its sides through which the flame issues. A ring 25, having perforations 26, is also preferably

used in this combination, the same being spaced from the drum 23 and supported by the plate 21, as shown.

In Fig. 4, I have shown a somewhat different form of chimney and flame controlling devices. The entire apparatus illustrated in Fig. 4 is adapted to rest directly upon the apparatus shown in Fig. 3, if desired, and will give good results when so arranged. The apparatus shown in Fig. 4 75 comprises a plate 27, adapted to rest upon the ring 25. This plate has a relatively large opening at its center, the edges of such opening being formed by a series of tongues or vanes 28, which are flared upwardly and given a twist, as clearly shown in the drawings. Resting upon the plate 27 and surrounding the flaring vanes 28 is a ring 29, the lower edge of which is cut to form a plurality of tongues 29^a, the ends of which are also flared outwardly. 80

Resting upon the ring 29 is the baffle plate combination 15, 16, 17, shown in Fig. 1.

Surrounding these baffle plates and rings 90 is a chimney 30, which is supported by the plate 27. The lower part of the chimney 30 is provided with a series of openings or windows 31, preferably of rhombic form, as shown in Fig. 7. Surrounding the chimney 95 at this point is a band 32, provided with a series of similarly shaped openings and capable of sliding around the chimney 30, so as to cause such openings to register to a greater or less extent, and in this way 100 serving to control the amount of air admitted to the chimney. The openings in the band 32 are preferably cut on three sides only, thus leaving metallic tongues 33, secured at one edge to the band. These 105 tongues are flared outwardly, as shown in Figs. 4, 8, and 9, so as to cause the air flowing through the openings in the band 32 to travel in a more or less tangential direction. This tends to produce a whirling motion 110 inside of the chimney, which tendency is augmented by the flaring tongues 28 and 29^a and by the angularly disposed blades 18 of the baffle plates 15 and 17.

While I have shown certain flame modifying and controlling devices, it will be understood that I am in no way limited to the specific arrangement shown, as many other devices can be successfully employed in connection with my improved burner. 115

While I have shown the burner and drums as being circular, and have referred to the fuel trough 8 as annular, it will be understood that these devices may be rectangular, elliptical, or of other configuration without in any way departing from the spirit of the invention. 120

Any of the well known liquid fuels, such as gasoline, kerosene, or crude oil, may be successfully employed in my improved 130

burner, but when the heavier oils are used, it is necessary to introduce a small quantity of gasoline or the like into the fuel trough at starting.

5. What I claim is:

1. A liquid fuel burner comprising a water basin, a fuel trough surrounding said water basin, and means for causing the flame from the burning fuel in said trough to curve downwardly over the edge of said basin, and impinge upon the surface of the water contained therein.

10. 2. A liquid fuel burner comprising an annular fuel trough, a water pan in which said trough is supported so that the trough is surrounded by water on both sides, and means for causing the flame from the burning fuel in said trough to impinge upon, enter into and vaporize the water on the 15. inside of said annular trough.

20. 3. A liquid fuel burner comprising a vertically disposed drum, an annular fuel trough extending around the inside of said drum near its bottom, and a water basin 25. inside of and surrounded by said fuel trough, the upper part of said drum being perforated, and means for drawing air through these perforations and for causing the flame from the burning fuel to curl down over the edge of said trough and impinge upon the water in said basin.

30. 4. A liquid fuel burner comprising an annular fuel trough, a combustion chamber comprising a drum supported by and spaced from the inner upper edge of said trough, and means for causing the flame from the burning fuel in said trough to be drawn inwardly and downwardly through the space between said trough and drum.

40. 5. A liquid fuel burner comprising an annular fuel trough, a combustion chamber comprising a separate drum of frusto-conical shape, having its lower edge supported by and spaced from the inner upper edge 45. of said trough so as to provide an annular

slot, and means for causing flame from the burning fuel to flow inwardly through this slot, said drum having a series of openings around its lower portion above said slot adapted to direct jets of air into such flame. 50

6. A liquid fuel burner comprising a vertical drum, an annular fuel trough disposed around the inside of the lower portion of said drum, means for supplying water to the basin formed inside of said fuel trough, 55 a second drum supported by and spaced from the upper edge of said trough, and means for producing a draft so as to cause the flame from the burning fuel in said trough to be drawn into said second drum 60 through the space between such drum and fuel trough, and to curl downwardly and impinge against the surface of the water in said basin.

7. A liquid fuel burner having an annular fuel trough, a combustion chamber comprising an open top drum spaced from the upper edge of said fuel trough, means for causing the flame from the burning fuel in said trough to be drawn inwardly through 70 the space between said trough and drum, and thence upwardly through said drum, and a baffle plate having angularly disposed blades between which the gases pass as they flow upwardly from said fuel trough. 75

8. A liquid fuel burner comprising a fuel trough, a combustion chamber adjacent the same, a chimney having openings above the combustion chamber for admitting air, and a circumferentially movable band having a series of openings adapted to register with said openings formed in the chimney, the said band having an outwardly flaring tongue at the one side of each opening therein, whereby the incoming air jets are 85 directed tangentially.

In testimony whereof I have affixed my signature.

LEE GARDNER.
